APPARATUS AND PROCESS FOR KILLING
HUMAN AND ANIMAL VERMINNorman D. Riker, Plandome, N. Y., assignor to
Lethelin Products Company, Inc., Manhasset,
N. Y.

Application June 3, 1933, Serial No. 674,143

4 Claims. (Cl. 119—160)

This invention relates to an apparatus and process for using the same, for killing human and animal vermin such as *Pediculus capititis*, *Pediculus pubis*, and *Pediculus corporis*.

5 In carrying out my process, I use, in combination with the garments to be hereinafter described, a very volatile liquid in the form of an organic ester or alcohol compound which very rapidly becomes a lethal or highly toxic
10 gas upon exposure to the air. It may be stated at this point that the trade-name of the liquid I have so far found useful for my purpose is "Lethelin" which is commercial methyl formate $HCOOCH_3$ having a boiling point of approximately 31° C., and which of itself is odorless.
15 While this particular liquid destroys the insect life at about the same speed as cyanide, it is harmless to human beings and animals. The liquid evaporates with great rapidity and will
20 penetrate any cloth or other material that is not gas-tight. In other words, the covering or garment must be gas-tight, although it may not be water-tight, as for treatment of some animals or fowl, a special paper bag treated with a
25 "slicker" material or the like may be used.

It very frequently happens that persons, particularly men, coming into hospitals, night lodging houses, and missionary settlements, are infested with vermin above described, and it is
30 the principal object of my invention to provide apparatus and a process for treating these persons and exterminating the vermin in a highly expeditious and not at all uncomfortable manner. Animals may be treated in a somewhat
35 similar manner.

The advantages of my apparatus and process will be more clearly apparent from a study of the specification taken in connection with the annexed drawings wherein:

40 Figure 1 shows how the hospital or settlement house, or mission may be provided with the necessary garments ready to be applied to the inmates, particularly the newly incoming ones.

45 Figure 2 is a sectional view of a garment adapted to fit the head of a human being.

Figure 3 shows how the human being may be substantially encased within a garment, only the hands and head being exposed.

50 Figure 4 is a sectional view on the line 4—4 of Figure 3, showing how the garment illustrated in Figure 3 may be closed up and rendered gas-tight.

55 Figure 5 shows the application of a garment in the form of a bag applied to a dog. Other

types of garments may be made to fit other animals.

In the drawings, Figure 1 shows the person having on two styles of garments. In this specification, "garment" is intended to mean either a cap for the head, a pair of trunks, or a complete suit such as shown in Figure 3, or a bag such as shown in Figure 5, or the equivalent.

1 is a head-cap which is preferably made 1 of flexible material, such as soft rubber, having a contractable band 2 which tightly fits around the head of the wearer. In this cap, is an absorbent pad 3 made of sufficient size to carry enough of a volatile liquid to kill the vermin 1 in the hair on the head within a few minutes' time. As shown, the pad 3 may be placed directly on the head, as the particular liquid specified will not harm the hair or scalp, but in the preferred form of head-garment shown 2 in Figure 2, the top part of the garment 1 is provided with a pocket having resilient gripping edges 4 for carrying the absorbent pad 3.

In this case, the pad 3 is of relatively stiff material which will hold its shape, and as shown 2 in Figure 2, the lower surface of the pad 3 is completely exposed; that is, no part of the garment is over it, so that the volatile gases coming from the pad will quickly pass downwardly and permeate through the hair and kill the *Pediculus 3 capititis*. For example, I have found that fifteen minutes in ordinary room temperature is sufficient.

Figure 1 also shows a pair of trunks 5, preferably made of a material the same as the cap 1, 3 having contractable bands 6 to fit tightly around the legs, and a contractable band 7 fitting around the body, and carrying an absorbent pad 8, over the hirsute portion of the mons pubis, similar to that shown in the head-garment in 4 Figure 2.

In Figure 3, a gas-tight suit is shown drawn over the clothing, only the hands and head being without the suit. In this case, the sleeves have contractable bands 9 to fit tightly around 4 the wrists, and the suit has also a contractable band 10 to fit around the neck. In order to get into this suit, the back is opened, and after the pads 3, two of which are shown, are saturated, the material of the suit is double-folded at the 5 seam as shown at 10 in Figure 4, and held in place by any suitable number of slideable clips 11. The suit may have a contractable band, as shown by dotted lines 14, to fit around each ankle, so that the foot portion 15 thereof may not be 5

required. Since the gas used will permeate clothing, all the insects or vermin, carried by the clothing and the part of the body covered by the clothing, will be exterminated. It is to be understood that after the person has been treated as above outlined, the garment or garments are removed and may be hung up or put away for the next patient.

In Figure 5, I have shown a dog enclosed, all but his head, within a bag 12 having a contractable band 13 fitting around the dog's neck. The part of the bag over the dog's back carries one or more of the removable pads 3 as described in the previous figures.

15 Special gas-tight paper bags may be used for treating other small animals and even potted house plants.

20 While I have shown, in Figure 3, a person equipped with a garment in the form of a special suit, the garment may be in the form of a bag, the same as shown enclosing the dog in Figure 5.

25 It is also to be understood that the garments and process may be used for private purposes, as well as for the particular purposes set forth in the early part of this specification. For example, sometimes children get affected with head-lice while at school, and they may be quickly treated at home in the manner herein 30 described. The process is especially advantageous in private treatment for *Pediculus pubis*, whereby the use of ointments, which soil the clothing, is eliminated by the more direct, easy and effective treatment herein described.

35 I claim:

1. The process of killing on human beings, vermin of the type described herein, which consists in taking a flexible, gas-tight garment, completely enclosing with the garment some time during the process that part of the human to be treated, positioning within the garment adjacent and above the part to be treated, an absorbent pad and applying to the pad, at any time before the complete closure of the garment in final position, a liquid which gives off a vapor heavier than air, is harmless to the skin which of itself is odorless, the liquid having the characteristic of speedy volatilization when exposed to air in a gas-tight enclosure as described and

developing a lethal gas which will quickly kill said vermin within thirty minutes or less.

2. The process of killing on live creatures, vermin of the type described herein, which consists in taking a flexible gas-tight garment having an absorbent pad located therewithin above the part to be treated, covering a portion of the creature to be treated with said garment and applying to said absorbent pad, before the coverage is fully completed, a quantity of a highly volatile liquid 5 harmless to the skin of said creatures, such as methyl formate having a boiling point of approximately 31° C., and having the property of speedily developing a heavy toxic gas on exposure to air and which will kill all vermin within 10 thirty minutes or less.

3. Means for carrying out the herein described process for killing human and animal vermin of the type described comprising; a liquid harmless to the skin of humans and animals and having 20 a boiling point of approximately 31° C. and developing rapidly a heavy lethal gas on exposure to air, and a gas-tight flexible garment to fit over a portion of the human or animal to be treated, said garment having at least one inside 25 pocket positioned facing the portion to be treated, and an absorbent pad to receive said liquid and adapted to be placed in said pocket so one side of the pad is exposed interiorly of the garment and which will kill all vermin within 30 thirty minutes or less.

4. Means for carrying out the herein described process for killing human and animal vermin of the type described comprising; a liquid harmless to the skin of humans and animals and 35 having a boiling point of approximately 31° C. and developing rapidly a heavy lethal gas on exposure to air, and a gas-tight flexible garment to fit over a portion of the human or animal to be treated, said garment having means for ensuring a substantial air-tight closure over said portion whereby said gas will kill all of said vermin within thirty minutes or less and also having absorbent pad holding means, and an absorbent pad to receive said liquid, said holding 40 means being located so the pad is held above the part to be treated and which will kill all vermin 45 within thirty minutes or less.

NORMAN D. RIKER.

CERTIFICATE OF CORRECTION.

Patent No. 2,033,357.

March 10, 1936.

NORMAN D. RIKER.

It is hereby certified that error appears in the printed specification of the above numbered patent requiring correction as follows: Page 1, first column, line 12, after "found" insert most; page 2, second column, lines 30-31 and 47-48, claims 3 and 4 respectively, strike out the words "and which will kill all vermin within thirty minutes or less"; and that the said Letters Patent should be read with these corrections therein that the same may conform to the record of the case in the Patent Office.

Signed and sealed this 21st day of April, A. D. 1936.
